ELECTRICAL DRIVING CIRCUIT

John W. Gray, Cambridge, Mass., assignor, by
mesne assignments, to the United States of
America as represented by the Secretary of War

Application February 27, 1945, Serial No. 580,021

4 Claims. (Cl. 179—171)

1

This invention relates in general to electrical circuits and more particularly to electrical circuits used to supply a controlling voltage to a load which draws a heavy current. This type of network is called a driver circuit.

According to conventional circuit practice, the driver is a cathode follower, which inherently has a high input impedance and a low output impedance. The high input impedance is desirable in order to match impedances with the usually high output impedance of the stage from which the driver controlling voltage comes. The low output impedance is desirable because of the linearity which is expected of a driver, and in order to match impedances with the load, which draws a heavy current and which usually has a low input impedance.

As is well understood in the art, however, a cathode follower has a non-linear response when a heavy load is drawn from it. Also, to obtain a sufficiently low output impedance from a cathode follower, it is often necessary to use a plurality of tubes in parallel, this involving extra expense and design difficulties in suppressing parasitic oscillations, which often build up between two or more tubes connected in this manner.

Among the objects of this invention, therefore, are:

1. To provide a driver circuit having a very high input impedance.
2. To provide a driver circuit having a very low output impedance.
3. To provide such a driver circuit which will have a linear response over a wide swing of the input voltage.
4. To provide such a driver circuit without the use of a plurality of tubes in parallel.

In accordance with the present invention there is provided a driver circuit comprising a pentode voltage amplifier, with the driver load making up a portion of the cathode circuit. The plate of the pentode voltage amplifier is connected to a cathode-coupled push-pull power amplifier having a very high gain. The circuit as a whole is made to have substantially 100 percent degenerative voltage feedback, and it can be shown mathematically that such a circuit has a very high input impedance and a very low output impedance.

For some purposes it may be desirable to have the constants of the cathode-coupled push-pull amplifier circuit such that the gain of this circuit is low. In this case the circuit would not have 100% degenerative voltage feedback

2

and the input and output impedances would differ from their aforementioned extreme values accordingly.

My invention will best be understood with reference to the drawing, in which is shown a circuit diagram of the complete driver circuit.

Referring now to the drawing, tube 1 is a pentode amplifier tube into which the controlling voltage is fed, in the cathode circuit of which are un-bypassed resistor 2 providing some current degeneration, and the driver load 3, the latter having connected in parallel therewith a series circuit consisting of condenser 4 and resistor 5. The load is shown grounded at the point 6. The other elements associated with tube 1 are a plate resistor 7, a screen-dropping resistor 8 and a screen by-passing condenser 9. The plate of tube 1 is coupled by means of condenser 10 to the grid of one triode tube 11 of the cathode-coupled push-pull amplifier. The grid is connected through resistor 12 to a positive bias from voltage divider 13. Tube 11 has its cathode directly connected to the cathode of tube 22, the cathodes being connected to ground through coupling resistor 23. The plates of tubes 11 and 22 are connected together through the primary of transformer 14. The secondary of transformer 14 is connected in parallel with the load 3. The plate of tube 11 is coupled to the ungrounded side of the secondary of transformer 14 by condenser 15. A portion of the output voltage is fed back to the grid of tube 22 by a voltage divider network, one branch of which is condenser 16 and resistor 17 in series, and the other branch of which is resistor 18 and a portion of voltage divider 13.

Referring now to the operation of the system, it can be seen that the cathode-coupled push-pull amplifier is a positive feed-back amplifier. Consider an increase in voltage on the grid of tube 22. This causes a decrease in the plate voltage of tube 22. This voltage change is applied to the primary of transformer 14 and fed to the secondary in the same polarity, as shown by the polarity marks. Since the grounded side of the secondary of transformer 14 cannot decrease in voltage, the ungrounded side of the secondary increases in potential, increasing the load voltage and thus increasing the grid voltage of tube 22. The feedback voltage is therefore in phase with the input voltage and so the feedback is positive. An increase in grid voltage on tube 22 will cause an increase in current through cathode resistor 23, an increase in voltage across resistor 23, and the grid-cathode voltage of tube

11 will be decreased. This decrease in grid-cathode voltage has the effect of increasing the plate voltage of tube 11, and of increasing the load voltage, due to the polarity of transformer 14. Therefore, any change in grid voltage of tube 22 is equivalent to a change 180° out of phase on the grid of tube 11.

It can be shown mathematically that the gain of an amplifier with positive feedback is:

$$K_{fb} = \frac{K_0}{1 - bK_0}$$

where K_{fb} represents the gain with feedback, K_0 is the gain with no feedback, and b is the fraction of the output voltage that is fed back. Neglecting the resistance of the portion of voltage divider 13, which is made comparatively small, b in this case is:

$$b = \frac{\text{resistance 18}}{\text{resistance 17} + \text{resistance 18}}$$

This ratio is made equal to

$$\frac{1}{K_0}$$

in this invention. Therefore,

$$K_{fb} = \frac{K_0}{1 - \frac{1}{K_0} \times K_0} = \frac{K_0}{0} = \text{infinity}$$

For some purposes the value of "b" is made much less than

$$\frac{1}{K_0}$$

In these cases the gain of the cathode-coupled push-pull amplifier is low.

Thus when "b" is made equal to

$$\frac{1}{K_0}$$

the gain of the cathode-coupled push-pull amplifier with respect to the grid of tube 22 is theoretically infinite, because it is at this grid that the voltage is fed back. But the gain of the amplifier with respect to the grid of tube 11 is infinite also, because of the cathode-coupled push-pull arrangement. In practice, the circuit is made to have a very high, not infinite, gain. To demonstrate that the driver has a very high input impedance, consider what happens when there is a positive change in the grid voltage of tube 1. The plate voltage of tube 4 will decrease, and this decrease is coupled to the grid of tube 11. The output of tube 11 is a large voltage increase, which change also occurs at the bottom of resistor 2. The value of resistor 2 is so chosen so that the increase in current flowing through it will produce a voltage across it which almost overcomes the increase in load voltage. The change in current in tube 1 is therefore quite small, and with a finite change in grid voltage, the effect is to provide a very high impedance.

To demonstrate that the driver has a very low output impedance, i. e., a very low impedance looking back at point 19, consider a decrease in the current drawn by the load. This tends to momentarily decrease the potential at point 19. This causes the cathode of tube 1 to lower, and the grid-cathode voltage to increase. This plate voltage therefore decreases, and this change is coupled to the grid of tube 11. The resultant increase in plate voltage of tube 11 tends to greatly increase the voltage at point 19, but the voltage drop across resistor 2 holds down the voltage at this point so that the resultant change in voltage

at point 19, i. e., across the load, is very small. Since the load current change was assumed finite, the output impedance is seen to be very low.

The driver circuit as a whole has substantially 5 100 percent degenerative feedback when "b" is made equal to

$$\frac{1}{K_0}$$

10 due to the fact that the gain of the cathode-coupled push-pull amplifier and the resistance of 2 are so chosen so that the gain between the input and point 19, the output, is unity.

Condenser 4 is put in parallel with the load in 15 order to increase the effective load impedance. Resistor 5, whose resistance is very small compared to the reactance of condenser 4, is used to lower the time constant of the load circuit.

Condenser 15 is used to couple changes in plate 20 voltage of tube 11 very quickly to the secondary of the transformer 14, without the usual transformer time lag. Without condenser 15 the cathode-coupled circuit tends to oscillate.

I claim:

25 1. A variable voltage, impedance transforming driver circuit comprising first, second and third electron tubes each having an anode, cathode and grid electrode, means to impress a control voltage between said first tube grid and ground, a load 30 having one end thereof grounded, an impedance coupling the ungrounded other end of said load to said first tube cathode, a common grounded cathode bias resistor to which said second and third tube cathodes are coupled, a push-pull output transformer to the primary ends of which said second and third tube anodes are coupled, the secondary end of said transformer having the same polarity as the primary end of said transformer to which said second tube anode is coupled 40 being connected to the junction of said load and said impedance, the other end of said secondary being connected to the grounded end of said load, said first tube anode being coupled to said second tube grid, and a voltage divider network across 45 said load to which said second tube grid is connected to derive a positive feedback voltage therefrom, said second and third tubes serving to amplify the variations in control voltage impressed upon said first tube grid and impress them across said load, whereby the voltage across the load will vary linearly with variations in control voltage.

2. The circuit recited in claim 1, wherein said voltage divider network comprises two resistances 55 in series having a ratio such that said positive feedback voltage impressed upon said third tube control grid substantially equals the reciprocal of the gain of said second and third tubes functioning as a push-pull amplifier without feedback. 60 3. The circuit of claim 1, further including capacitor means for connecting said second tube anode with said junction of said load and said impedance.

4. A driver circuit comprising a vacuum tube 65 phase inverter amplifier having cathode, anode and grid circuits, said anode and cathode circuits respectively including impedances therein, means for impressing control potentials between said grid circuit and ground, a high gain amplifier, means for feeding back a portion of the output from said high gain amplifier as a positive voltage feedback thereto, the ratio of the feedback voltage to the output voltage of said high gain amplifier being equal to the inverse of the gain of said high gain amplifier without said feedback, the gain of

said high gain amplifier with said regenerative feedback thus being substantially infinite, load impedance means having one end thereof grounded, means for coupling the output of said phase inverter amplifier as an input to said high gain amplifier, said high gain amplifier being connected across said load impedance means, and means coupling the ungrounded end of said load impedance means to said cathode impedance so that the potential developed across said load impedance means is applied as a negative feedback to the cathode circuit of said phase inverter amplifier, whereby said control potentials will produce a linear variation in potential across said driver load means.
